UNITED STATES PATENT OFFICE

116,978

DESIGN FOR AN AGITATOR

Fred A. Conterman, Jamestown, N. Y., assignor
to Blackstone Manufacturing Company, Inc.,
Jamestown, N. Y., a corporation of New York

Application May 23, 1939, Serial No. 85,158

Term of patent 14 years

To all whom it may concern:

Be it known that I, Fred A. Conterman, a citizen of the United States, residing at Jamestown, in the county of Chautauqua and State of New York, have invented and produced a new, original, and ornamental Design for an Agitator, of which the following is a specification, reference being had to the accompanying drawing, forming part thereof; and in which—

I claim:

The ornamental design for an agitator, substantially as shown.

FRED A. CONTERMAN.
